G. HAFNER

HEATER

Filed Jan. 12, 1924

INVENTOR
G. Hafner

BY

F. Lehmann
ATTORNEY

UNITED STATES PATENT OFFICE.

GEORG HAFNER, OF NEW YORK, N. Y.

HEATER.

Application filed January 12, 1924. Serial No. 685,733.

To all whom it may concern:

Be it known that I, GEORG HAFNER, a citizen of the United States, residing at New York, in the county of New York and State 5 of New York, have invented certain new and useful Improvements in Heaters, of which the following is a specification.

The main object of this invention is to provide a heater used in conjunction with a 10 gas or coal stove, the purpose being to set the heater upon the stove over the exposed lid opening through which an air draft is introduced over the grate of the heater.

Another object is to provide a heater having a firing grate mounted therein and an 15 additional circular flue channel, the air passing upwardly through the grate and thence into the circular channel from which said draft is released by passing through the lid 20 opening of a stove and into a chimney flue.

These and other objects will become apparent in the description below, in which characters of reference refer to like-named parts of the drawing.

Referring briefly to the drawing, Figure 25 1 is a front elevational view of the heater.

Figure 2 is a sectional elevation view taken on line 2—2 of Figure 1.

Figure 3 is a cross-sectional view taken on 30 line 3—3 of Figure 1.

Figure 4 is a cross-sectional view taken on line 4—4 of Figure 2.

Referring in detail to the drawing, the 35 numeral 10 indicates an outer circular casing which is provided at its lower end with a reinforcing ring 11, and at its upper end with a cover 12. A relatively large opening 13 in the cover 12 is provided with an annular shoulder 14 upon which a circular 40 lid 15 is supported. Within the outer casing, an upright inner casing 16 having a bottom 17 which is supported above the lower edge of the outer casing is rigidly fixed. The bottom 17 is raised above the 45 lower edge 18 of the casing and is rigid with the casing in order to support the weight of the inner casing. A rectangular opening 19 passes through the outer casing and the inner casing near their lower ends, and the 50 spaces between the inner and outer casings and the sleeve are sealed by walls 20. This opening is provided in order to permit re-

moval of ashes which fall from the grate 21, the latter being mounted on brackets 22 intermediate the height of the sleeve. Near 55 the upper end of the inner casing, additional brackets 23 are provided and are firmly anchored to the wall of the inner casing. These brackets support an inverted conical baffle plate 24. This baffle plate is circular 60 and at its center has a circular opening 25 in which a pair of semi-circular doors 26 and 27 are mounted. These doors are provided with spring hinges 28 which normally retain the doors in the position shown in 65 Figure 2. The arrows illustrated in Figure 2 are used to indicate the direction of flow of draft which enters the ash pit 29 thru the opening 19 and passes upwardly between the bars 30 of the grate. After passing 70 through the fire, the draft passes through the circular space 31 formed between the baffle plate 24 and the sleeve 16. From thence the draft passes downwardly on the 75 outside of the inner casing and between it and the outer casing, thereafter passing directly through the lid opening 32 of an oil or gas stove.

In use, the heater is placed over the lid 80 opening of a stove so that a draft is induced in the manner previously mentioned. In order to stock the heater with fuel, the latter is passed through the doors 26 and 27 after the same have been rotated downwardly to open position. By lifting the lid 15, a quantity of coal or other suitable fuel may be dumped upon the baffle plate 24 which serves as a suitable receptacle therefor, and the doors 26 and 27 will open of their own accord, due to the downward pressure of the 85 fuel thereon, thereby precipitating said fuel upon the grate.

I claim:—

A heater comprising an outer circular casing open at the bottom, a lid closing the upper end of the outer casing, an additional inner casing mounted concentrically in the outer casing, said inner casing being closed at the bottom and open at the top, the inner casing communicating with the outer casing at the top of the heater walls connecting the inner and outer casings at the bottom and bounding an opening communicating with the chamber of the inner casing, a 95 100

grate mounted in the inner casing above the opening, a conical baffle mounted inverted in the upper end of the inner casing, said baffle having an opening therein, semi-circular doors normally closing, said opening and spring actuated hinges supporting said doors, the air circulation being adapted to enter the inner casing through the opening

beneath the grate and course upwardly around the baffle and then downwardly between the inner and outer casings and out through the lower open end of the outer 10 casing.

In testimony whereof I affix my signature.

GEORG HAFNER.
